UNITED STATES PATENT OFFICE.

JAMES H. BALL, OF CALUMET, MICHIGAN.

RAIL-STOP FOR RAILWAY ROLLING-STOCK.

1,058,708.

Specification of Letters Patent.

Patented Apr. 15, 1913.

Application filed May 31, 1912. Serial No. 700,729.

To all whom it may concern:

Be it known that I, JAMES H. BALL, a citizen of the United States, and a resident of Calumet, county of Houghton, State of Michigan, have invented certain new and useful Improvements in Rail-Stops for Railway Rolling-Stock, of which the following is a full, clear, and exact description.

The invention relates to a rail lock or stop for railway rolling stock and seeks to provide a simple, effective construction which is adapted to be secured to the rail to block the movement of locomotives or cars.

The invention consists in the features of improvement hereinafter set forth, illustrated in the preferred form in the accompanying drawings and more particularly pointed out in the appended claims.

In the drawings, Figure 1 is a plan view 20 of the improved rail stop or lock. Fig. 2 is a longitudinal section on the line 2—2 of Fig. 1. Fig. 3 is a detail horizontal section on the line 3—3 of Fig. 2, and Fig. 4 is a cross-section on the line 4—4 of Fig. 1.

25 The body portion 10 of the improved rail lock or stop is adapted to extend over the head 11 of the railway rail 12. In the form shown, the body portion is provided with a raised central part 13 having a flat, upper face *a*, inclined end faces *b* and *c*, a concaved face *d* on one side and a convex face *e* on its opposite side. This body portion may be otherwise formed. The particular shape shown can be readily grasped by placing the 35 thumb against the concave side face *d* and the fingers over the convex side face *e*.

The body portion is provided with suitable means whereby it may be securely fastened to the rail and for this purpose is provided with depending side portions or flanges 14 and 15. The side flange 14 is somewhat wider than the side flange 15 and is provided at its lower edge with an in-turned lip 16. This side flange is adapted 45 to fit against one side of the head 11 of the rail, with the lip 16 extending beneath the head of the rail and abutting against the web thereof, as most clearly shown in Fig. 4. The opposite side flange 15 is provided 50 at its lower end with an in-turned lip 17 of rectangular section and a wedging key 18 is adapted to fit between the flange 15 and

the adjacent side of the rail head to securely clamp the stop body in position. The key is preferably provided on its outer side with 55 a longitudinally extending groove 19 within which the lip 17 extends, the inner edge of the lip and the bottom wall of the groove being inclined or tapered, as most clearly shown in Fig. 3, so that, as the wedge is 60 forced into the position shown between the side flange 15 and the rail head, the opposite side flange 14 of the lock body and lip 16 thereon will be drawn snugly into engagement with the head of the rail. Preferably, 65 as shown, the upper face of the wedge engages the under side of the upper portion of the lock body and the inner face of the wedge or key is adapted to fit against the side of the rail head, the key being provided 70 with a lip 20 which extends beneath the head of the rail. To lighten the wedging key, it is provided on its upper and lower edges with longitudinal grooves 21 and, to prevent the loss of the key, is preferably connected 75 to the lock body by a chain 22. In the form shown, the chain is fastened at its ends to perforated, laterally projecting lugs 23 and 24 upon the adjacent, side end portions of the lock body and the wedge. This chain, 80 (see Fig. 2) is of sufficient length to permit the withdrawal and insertion of the wedging key.

The lock or stop body having the depending side flanges 14 and 15 is preferably 85 formed of a steel casting and each side portion and depending flange is provided with a series of transverse strengthening flanges 25 and 26. The wedging key 18 is preferably formed of a piece of cast steel and can 90 be conveniently manipulated to quickly secure the lock body to the rail or release it therefrom. The lips 16 and 17 on the side flanges are sufficiently far apart to permit the passage of the rail head between them 95 when it is inclined to one side at an angle of about 45°.

The body is placed on the rail by inclining it to one side, placing the lip 16 against one side of the web beneath the rail head 100 and rolling the body over the rail. The lock body is then slid to desired position adjacent the wheel of the locomotive or railway car and secured in position by

means of the wedging key. The side flange 14 with its lip 16 and the key with its lip or flange 20 conform snugly to the head of the rail and securely hold the lock body in position.

The under side of the main body portion of the lock is preferably provided with a longitudinal recess 27 (see Figs. 1 and 2) so that the under face thereof is spaced somewhat above the tread of the rail. A stop dog 28 extends through an inclined guide-way 29 in the body of the stop device and is preferably held in position by a pin 30 which fits in an opening in the dog and extends through a slot 30 formed in the lock body at right angles to the guide way 29. The guide-way 29 is inclined at an angle of 45° to the horizontal and the stop dog has a limited motion therethrough to the extent allowed by the pin and slot connection between it and the lock body. The construction is such that the stop dog is held above the center of the rail and its upper end is arranged to engage the tread 33 (see Fig. 2) of the locomotive or car wheel. Preferably, the upper, wheel engaging end 34 of the stop dog is slightly rounded or crowned, as shown, to properly engage worn wheels and also to allow for the angle of the wheel tread.

The stop dog is preferably formed of carbon steel. Its lower end 35, which is adapted to engage the tread of the rail, is chisel hardened and ground at right angles so that knife edges 36 are provided. Any movement of the locomotive or railway car will exert pressure on the stop dog and one of the knife edges 36 will bite into the rail to thereby prevent movement of the stop dog and of the locomotive or railway car. Preferably, the stop dog is made as short as possible, but it should be of sufficient length to prevent the wheel or any portion of the wheel from engaging the body of the stop device.

The improved rail lock or stop is preferably used in pairs, one being of right hand and the other of left hand construction and so arranged that the wedging keys are placed upon the outer side of the rail.

A pair of improved lugs or stops can be readily placed in position and engaged with the wheels of a locomotive or car for blocking the same against movement.

The improved construction is particularly adapted as a safety device for blocking locomotives in roundhouses and at railway terminals. It can also be used with convenience in car repair shops. By forcing a car against one of the improved rail stops, the end of the car may be raised for convenience in making repairs. The construction is inexpensive and of light weight and can be readily and conveniently placed in position and removed therefrom. By

driving out the pin 30, the stop dog can be removed and its lower, rail engaging end resharpened.

It is obvious that changes may be made in the details set forth without departure from the essentials of the invention as defined in the claims.

I claim as my invention:—

1. A rail-stop comprising a body portion adapted to be secured to the rail, and a stop-dog mounted in a guide-way in said body portion and having a sharpened lower end adapted to bite into the rail. 75

2. A rail-stop for railway rolling stock comprising a body portion arranged to extend over and be clamped to the head of the rail, and a wheel-engaging dog mounted in an inclined guide-way in said body portion and having a sharpened edge at its lower end for engaging the rail. 80

3. A rail-stop comprising a body portion arranged to extend over the rail, means for securing said body portion to the rail head, and a stop dog mounted in an inclined guide-way said body portion having a wheel-engaging upper end and a rail engaging lower end. 85

4. A rail-stop comprising a body portion arranged to extend over the rail, means for securing said body portion to the rail head, and a wheel-engaging dog mounted in an inclined guide-way in said body portion and having a square lower end provided with a cutting edge for engaging the rail. 95

5. A rail-stop comprising a body portion adapted to extend over the rail and having a flange for engaging the head of the rail, a wedging key for locking said body portion on the rail, and a stop dog mounted in an inclined guide-way in said body portion 100 and having wheel and rail engaging ends. 105

6. A rail-stop comprising a body arranged to extend over the rail, provided with wheel-engaging means and having depending side flanges with inturned lips at 110 the lower edges of said flanges, one of said lipped flanges being arranged to engage one side of the rail-head, and a wedging key grooved on its opposite sides to fit over the lip of the other side flange and against the 115 opposite side of the rail head.

7. A rail-stop comprising a body arranged to extend over the rail and having depending side flanges provided with in-turned lips, one of said lipped flanges forming a jaw for engaging one side of the rail head, a wedging key adapted to fit between the other of said flanges and the opposite side of the rail head and having a lip arranged to extend beneath the rail head, and a stop-dog mounted in an inclined guide-way in said body and having a wheel-engaging, upper end and a sharpened, rail-engaging, lower end. 120

8. A rail-stop comprising a body adapted 125

to extend over the rail and having depending side flanges, one of which is adapted to fit against the rail head, a wedge key adapted to fit between the rail-head and the opposite side flange, and a stop dog mounted in an inclined guide-way in said body and having a wheel engaging upper end and a

sharpened rail-engaging lower end, said dog having a pin-and-slot connection with said body.
